WEB PASTING DEVICE

Allen B. Staiger, Atlantic City, N. J.

Application August 21, 1930. Serial No. 476,768

4 Claims. (Cl. 91—51)

The object of the invention is to provide improvements in devices for applying paste or other liquids and semi-liquids to webs of various sorts, but more especially to strips or lengths of wallpaper and the like.

Another object is to provide in such a device means for so regulating the rotation of what will be termed the paste-applying roll that in passing around a portion of its surface the paper web will slip or move with respect thereto.

10 A further object is to provide an improved weight for the device, so constructed as to permit its remaining in inoperative position, or to rest in operative position when desired, but in spaced relation with said roll, in such latter position being operative to yieldingly retain the paper web in predetermined frictional cooperation with said roll.

20 Still another object is to provide in such device an idler roll, operative to maintain the paper web in engagement with the paste-applying roll, but with end portions of less diameter than its central portion, said end portions being in normal spaced relation with the marginal portion 25 of the web, to prevent the carrying of paste from one web to another.

25 And a still further object is to provide in this device a removable paste container, having at least one side composed of gauze through which 30 paste is adapted to flow into the principal container into which the paste-applying roll extends.

35 With these and other objects in mind, the present invention comprises further details of construction and operation which are fully brought out in the following description, when read in conjunction with the accompanying drawing, in which Fig. 1 is a perspective view of one embodiment of the invention; Fig. 2 is a transverse vertical section of the same; Fig. 3 is a perspective view of the paste container; and Fig. 4 is a similar 40 view of the roll regulating spring.

45 Referring to the drawing, a container comprises a bottom 1, end walls 2, and front and rear walls 3 and 4, respectively. A paste container or reservoir, shown per se in Fig. 3, comprises an annular relatively stiff frame 5, having spaced depending lugs 6 for detachable engagement with the end and rear walls of said first container, while depending from said frame is a preferably 50 rectangularly shaped gauze or equivalent body portion 7, the essential feature of which is that the forward wall 8, that is the one facing the front wall 3 of said first container, is apertured or formed of gauze, while the other walls of said 55 paste container may be imperforate if desired.

From the end walls 2 there arise spaced brackets 9 carrying lugs 10 and 11, while supported by and extending between said brackets is a rotatable paste-applying roll 12, adapted to be manually turned when desired by means of a crank 60 12', while said roll also extends downwardly into said first container in order to there receive paste or other liquid which has flown into said first container from the so-called paste container. An angular spring, shown per se in Fig. 4, comprises a free end portion 13 and a relatively fixed portion 14, the latter being provided with an aperture 15 and an angularly deflected flange 16 closely adjacent thereto. This spring is normally positioned, as shown in Fig. 2, with its angular portion 17 supported preferably at or adjacent to the junction of the bottom wall 1 and forward wall 3 of said first container, while a manually rotatable bolt or screw 18 extends through said forward wall, through the aperture 15 in said spring and engages a nut 19, which is prevented from rotation with respect to said spring by engagement with the flange 16. Above the bolt or screw 18, the forward wall 3 of said container is preferably deflected inwardly to provide a flange 20 for a purpose hereinafter described.

Pivottally carried at 21 by the brackets 9 are two oscillatable arms 22 which by engagement with the lugs 10 are yieldingly maintained in an upper or retracted position, and by engagement 85 with the lugs 11 are prevented from dropping below a certain predetermined angular position. Between these arms extends a rotatable idler roll 23, having conical ends 24, while said arms are also connected by means of a strap or the like 25, to which is detachably secured a weight 26 and a preferably non-corroding angularly bent guard 27. The free edge portion 28 of this guard preferably rests against the weight 26, or is otherwise fixed with respect to the strap 25.

95 In the operation of the device a web 29 is threaded through the device, as shown in Fig. 2, so that it first passes over the wall flange 20, thence beneath the guard 27, over a portion of the surface of the roll 12, and thence beneath and partially around the idler 23. If the web is then drawn in the direction of the arrow, it will cause the roll 12 to rotate and thereby lift paste or other liquid from said first container towards and spread it upon the under surface of said web, 100 the latter being maintained in frictional engagement with said roll by means of the weighted guard and idler. However, by properly adjusting the tension of the spring 13—14 by means of the screw 18, the roll 12 while continuing to rotate 105 110

will not rotate with as fast surface speed as of the web passing across its surface, and in this way the amount of paste or other liquid or semi-liquid applied to the web may be accurately varied. Depending upon the relative stiffness, thickness, flexibility, or other structural characteristics of the web 29, the weighted guard is adapted to rise and fall and thus automatically maintain a substantially predetermined engagement of the web with the paste-applying roll.

Having thus described my invention, what I claim and desire to protect by Letters Patent of the United States is:—

- 15 1. A web pasting device, comprising a paste container, a paste-applying roll extending into said container, a bracket carried by said container and rotatably supporting said roll, and a gravity-actuated weight oscillatably carried by said bracket and extending parallel with the 20 axis of said roll, to frictionally engage a paper web and remove wrinkles therefrom and yield in accordance with the stiffness of such web to maintain said web in substantially uniform frictional engagement with said roll.
- 25 2. A web pasting device, comprising a paste container, a paste-applying roll extending into said container, a bracket carried by said container and rotatably supporting said roll, and a weight oscillatably carried by said bracket and extending parallel with the axis of said roll, to frictionally engage a paper web and yield in accordance with the stiffness of such web to maintain said web in substantially uniform frictional

engagement with said roll, a wall of said container terminating in a curved flange in contact with which a web passes and also parallel with the axis of said roll, and said weight engaging the opposite surface of a web between said flange and said roll to further insure the removal of wrinkles from the web.

3. A web pasting device, comprising a paste container, a paste-applying roll extending into said container, a bracket carried by said container and rotatably supporting said roll, an arm oscillatably carried by said bracket, an idler carried by said arm, and a weight also carried by said arm parallel with the axis of said roll, a demountable member carried by said weight and providing a pronounced edge therefor, adapted to frictionally engage a paper web and with said idler retain such web in engagement with said roll, a wall of said container being provided with a flange across and in contact with which the web passes and said weight engaging the web between said flange and said roll.

4. A web pasting device, comprising a paste container, a paste-applying roll extending into said container, a V-shaped spring, having its 100 angular portion bearing as a fulcrum against one wall of said container and having one of its arms normally bearing directly against said roll, and adjustable means connecting the other arm of said spring to said container wall and operative 105 to vary the pressure of said first arm against said roll.
